DESIGN FOR A CLOCK CASE

Amos E. Northup, Royal Oak, Mich., assignor to
General Electric Company, a corporation of
New York

Application August 13, 1935, Serial No. 58,103

Term of patent 14 years

To all whom it may concern:

Be it known that I, Amos E. Northup, a citizen of the United States, residing at Royal Oak, in the county of Oakland, State of Michigan, have invented a new, original, and ornamental Design for a Clock Case, of which the following is a specification, reference being had to the accompanying drawing, forming a part thereof.

In the drawing, Fig. 1 is a front view; Fig. 2 is

a side view; and Fig. 3 is a top view of a clock case showing my new design.

I claim:

The ornamental design for a clock case as shown

In witness whereof, I have hereunto set my hand.

AMOS E. NORTHUP.
